ABSTRACT

A safety belt buckle so constructed that the minimum number of components are employed for convenience and simplicity of assembling; a movable portion is enclosed by a cover plate and a baseplate so as to be protected from an unexpected impact of any other object, in order to preclude an unexpected disengagement of the tongue from a latched position; and disengagement of the tongue is precisely effected only by pressing on it by means of a finger inserted through an aperture on the cover plate, but is not unexpectedly effected as a result of the force of inertia exerted thereon on collision.

SAFETY BELT BUCKLE

The present invention relates to a safety belt buckle. More particularly, the present invention relates to a safety belt buckle characterized by comprising a cover plate secured to the baseplate; a latch plate having one end engaged with one end of the baseplate within said cover plate and pivotally supported so that the latch plate can move swingably. At the other end, an operative portion is bent or folded to extend under an inner or under surface of the cover plate, said operative end portion of the latch plate being in contact with the undersurface of the cover plate to prevent the latch plate from being pressed upwardly by the force applied by the below-mentioned spring. A spring is secured to the latch plate and presses said latch plate towards the cover plate. An aperture is provided at one part of the cover plate corresponding to the operative end portion of the latch plate.

The structure of the conventional safety belt buckle is such that the latch element for engagement of the tongue is released by rotating a swingable cover plate in an unlatching direction by means of a lever pivotally secured to the rear portion of the baseplate. The conventional safety belt buckle has defects, namely, that the structure is complicated and assembling is troublesome, because numerous components are used. It has another functional defect that an unexpected disengagement of the tongue from the latched position has been often encountered, since the force of inertia, on collision, is exerted thereupon in a direction causing unlatching of the tongue.

In view of the defects of the conventional safety belt buckle, a principal object of the present invention is to provide a safety belt buckle so constructed that the minimum number of elements are employed for convenience and simplicity of assembling; a movable portion is enclosed by a cover plate and a baseplate so as to be protected from an unexpected impact of any other object, in order to preclude an unexpected disengagement of the tongue from the latched position; and disengagement of the tongue is precisely effected only by pressing thereon by means of a finger inserted through an aperture on the cover plate, but is not unexpectedly effected by the force of inertia.

The accompanying drawings show a preferred embodiment of a safety belt buckle of the present invention, wherein,

FIG. 1 is an exploded perspective view;

FIG. 2 is a plan view;

FIG. 3 is a plan view, with parts cut away; and,

FIG. 4 is a sectional view, taken along the line A—A of FIG.

3.

The following description will be made with reference to the accompanying drawings.

Numerical 1 is a baseplate, which consists of a pair of standing and inwardly folded flange portions 2, 2 each having at one end thereof a slightly rising end surface 6 with a notch or slit and having a cutout portion 7, at the opposite end thereof, for engagement with a cover plate. A web portion has a reentrant edge portion 3 at the rear or right end in FIG. 1, an aperture 5 extending over substantially the entire width thereof near the opposite front or left end part thereof, and a projection 4 formed integrally therewith, for supporting a free end of a tongue 26. The projection 4 is centrally located and extends perpendicular to the web.

Numerical 8 is a latch plate, which has one end fitted to said reentrant edge portion 3 so as to pivotally support the latch plate whereby the opposite end portion of said latch plate can swing. A guide aperture 9 is provided at a position corresponding to the supporting projection 4, for receiving said projection therein, and said aperture having at one end thereof an upwardly raised latch portion 10. An upstanding portion 11 extends substantially perpendicularly at a position spaced leftwardly or frontwards from the latch portion 10 and then is bent perpendicularly to extend frontwardly to form an operative portion 12 with a plane surface. The operative portion 12, at an upper surface thereof, is normally maintained in contact with the undersurface of a cover plate 14.

The cover plate 14 has an upright front or left end portion 15 provided with slits 16, 16 at an upper part thereof, and is attached to the baseplate 1 with the slits 16, 16 interfitting with the cutout portions 7, 7, respectively. The cover plate has at its right end edges 17 which are hooked over each of rising end portions 6, 6. It is to be noted, as best seen in FIG. 4, that a gap 18 is formed between the baseplate 1 and the cover plate 14, so as to permit insertion of the end of tongue 26.

Numerical 19 is a spring, which has a reentrant edge 20 at one end and a forked portion 21 with a space for permitting passage of the supporting projection 4, at the opposite end. Said spring 19 is formed in a downwardly or backwardly bent shape, like a bow, and is attached to the latch plate 8 along the undersurface thereof, with the reentrant edge 20 fitted to the slit 13 and with the end of the forked portion 21 contacting the left or front part of the baseplate 1, so that the latch plate 8 is pressed upwardly to an extent, due to resilience of the spring, that a narrow gap or space substantially equal to a thickness of the tongue 26 is formed between the undersurfaces of flange portions 2, 2 and a portion defined by the latch portion 10 and the upstanding portion 11 of said latch plate, and that the operative portion 12 thereof is maintained in contact with the undersurface of the cover plate 14. Around a portion of the cover plate 14 in contact with the upper plane surface of operative portion 12 of the latch plate, an aperture 22 is provided corresponding to said operative portion.

Numerical 23 is a packing plate, which is firmly fixed around the supporting projection 4 to preclude a loose engagement of the supporting projection with the end portion of the guide aperture 9 defined by the latch portion 10. Numerical 24 is a belt bar, which is engaged within the baseplate and around which is wound a belt 25 inserted into the buckle through the aperture 5.

The operation will be described with reference to FIG. 4 of the drawings.

If the tongue 26 with an aperture 27 near a front free end thereof is inserted into the buckle through the gap 18 along the undersurfaces of the flange portions 2, 2, the front free end of the tongue 26 passes inwardly beyond the latch portion 10 of the latch plate 8 and presses said latch plate downwardly against the pressure of the spring 19 on the undersurface of the latch portion, until the aperture 27 becomes engaged with the latch portion 10 at its one end contiguous to the front free end, thereby locking the tongue within the buckle, as shown in the drawing.

In order to release the tongue from the latched position, the operative portion 12 of the latch plate 8 is pushed downwardly as appearing in FIG. 4 by pressing on it by a finger inserted through the aperture 22, so that the entire latch plate 8 swings about the reentrant portion 3 as a fulcrum to push the latch portion 10 downwardly below the upper end of the supporting projection 4, whereby the aperture 27 of the tongue 26 is disengaged from the latch portion 10 of the latch plate, thus effecting release of the tongue from the buckle, with extreme ease.

The safety belt buckle of the present invention has the advantage of simplicity in construction and assemblage, since a minimum number of components are used, including the baseplate 1, the cover plate 14, the latch plate 8 with the integrally formed operative portion, the spring 19 and the belt bar. Other advantages of the safety belt buckle of the present invention are that the tongue is easily released from the latched position simply by pressing the operative portion of the latch plate 8 through the aperture of the cover plate, and an unexpected disengagement or release of the tongue is precluded since engagement of the tongue with the latch plate is forced in its positive direction due to force of inertia exerted thereupon on collision.

What is claimed is:

1. A safety belt buckle, comprising:
a baseplate having a hooklike reentrant portion at one end thereof defining integral fulcrum means;

a latch plate having first and second generally parallel transversely offset portions extending respectively in opposite directions from a transversely extending intermediate connecting portion, one end of said first portion of said latch plate extending into said reentrant portion and being pivotally engaged with said fulcrum means whereby said latch plate is swingable with respect to said baseplate, said first portion having latch means thereon; a spring pivotally urging said latch plate about said fulcrum means away from said baseplate; a cover plate secured to said baseplate and overlying said latch plate, said second portion of said latch plate normally contacting the inner surface of said cover plate under the urging of said spring whereby said cover plate limits swingable movement of said latch plate away from said baseplate, said cover plate having an aperture therethrough in the part thereof contacting said second portion of said latch plate whereby a user's finger can be inserted through said aperture to swing said latch plate toward said baseplate, said aperture being laterally offset from said latch means whereby said latch plate can be moved by a relatively light force.

2. A safety belt buckle according to claim 1, wherein one end of said spring is provided with a curved hooklike portion thereon in which is received said one end of said latch plate, said spring being upwardly bowed between its ends and the other end of said spring slideably engaging said baseplate, and an intermediate portion of said spring slideably engaging said latch plate for resiliently urging same upwardly toward said cover plate.

3. A safety belt buckle, comprising:

a baseplate having integral fulcrum means adjacent one end thereof; a latch plate having first and second generally parallel transversely offset portions extending respectively in opposite directions from a transversely extending intermediate connecting portion, said first portion being pivotally engaged with said fulcrum means whereby said latch plate is swingable with respect to said baseplate, said first portion having latch means thereon; a spring pivotally urging said latch plate about said fulcrum means away from said baseplate; a cover plate secured to said baseplate and overlying said latch plate, said second portion of said latch plate normally contacting the inner surface of said cover plate under the urging of said spring whereby said cover plate limits swingable movement of said latch plate away from said baseplate, said cover plate having an aperture therethrough in the part thereof contacting said second portion of said latch plate whereby a user's finger can be inserted through said aperture to swing said latch plate toward said baseplate, said aperture being laterally offset from said latch means whereby said latch plate can be moved by a relatively light force; said baseplate having an integral upstanding projection extending toward said cover plate and terminating in spaced relation thereto, said spring having spaced-apart legs between which said projection extends, said first portion of said latch plate having an opening through which said

projection can extend; and said spring comprises a bowed, forked, platelike member having one end thereof positioned adjacent said fulcrum means and disposed in engagement with one end of said latch plate, the other end of said spring being disposed in slideable bearing engagement with said baseplate, said spring further including intermediate portions spaced upwardly from said baseplate and maintained in slideable bearing engagement with said latch plate for normally, resiliently, pivotally urging same about said fulcrum means upwardly toward said cover plate.

4. A safety belt buckle, comprising:

a baseplate having integral fulcrum means adjacent one end thereof;

a latch plate having first and second generally parallel transversely offset portions extending respectively in opposite directions from a transversely extending intermediate connecting portion, said first portion being pivotally engaged with said fulcrum means whereby said latch plate is swingable with respect to said baseplate, said first portion having latch means thereon;

a spring pivotally urging said latch about said fulcrum means away from said baseplate;

a cover plate secured to said baseplate and overlying said latch plate, said second portion of said latch plate normally contacting the inner surface of said cover plate under the urging of said spring whereby said cover plate limits swingable movement of said latch plate away from said baseplate, said cover plate having an aperture therethrough in the part thereof contacting said second portion of said latch plate whereby a user's finger can be inserted through said aperture to swing said latch plate toward said baseplate, said aperture being laterally offset from said latch means whereby said latch plate can be moved by a relatively light force;

said baseplate having an integral upstanding projection extending toward said cover plate and terminating in spaced relation thereto, said spring having spaced-apart legs between which said projection extends, said first portion of said latch plate having an opening through which said projection can extend.

said latch means being defined by an upwardly raised section located at the end of said opening in the first portion of said latch plate;

said baseplate being generally channel shaped in cross section and having inwardly extending flanges overlying and spaced from the central web thereof, said flanges having one end thereof upturned portions on which are hooked edge portions of said cover plate, said central web having at said one end of said baseplate reentrant portions defining said fulcrum means, said one end of said latch plate extending into said reentrant portions, said one end of said latch plate having a notch therein, one end of said spring being backwardly curved and being received in said notch and hooked onto said latch plate, said spring being upwardly bowed between its ends and the other end of said spring slideably engaging said central web of said baseplate.
